Primary Examiner—Ruth McInroy
Attorney, Agent, or Firm—Richard C. Litman[57] **CLAIM**

The ornamental design for a combined smoke and fume shield, as shown and described.

DESCRIPTION

FIG. 1 is a combined smoke and fume shield showing my new design;

FIG. 2 is a front elevational view thereof, the left, right and rear sides being identical;

FIG. 3 is a top plan view thereof; and,

FIG. 4 is a bottom plan view thereof.

The broken line showing in FIG. 1 of the head of a person wearing the present invention is for illustrative purposes only and forms no part of the claimed design.
